UNITED STATES PATENT OFFICE.

ANTONIO PAPINI, OF PHILADELPHIA, PENNSYLVANIA, ASSIGNOR TO A. MECKY COMPANY, OF PHILADELPHIA, PENNSYLVANIA, A CORPORATION OF PENNSYLVANIA.

DEVICE FOR CLAMPING FLUID-HEATERS WITH SUPPLY MEMBERS.

1,345,396.

Specification of Letters Patent.

Patented July 6, 1920.

Application filed August 11, 1919. Serial No. 316,554.

To all whom it may concern:

Be it known that I, ANTONIO PAPINI, a subject of the King of Italy, having resided in the United States one year last past and 5 having declared my intention of becoming a citizen thereof, residing in the city and county of Philadelphia, State of Pennsylvania, have invented a new and useful Device for Clamping Fluid-Heaters with Supply Members, of which the following is a 10 specification.

My invention consists of a novel device for clamping a heater for water or other fluid to a faucet or like supply member, and 15 placing the heater in communication with the faucet, and if desired, supporting it on the latter, as will be hereinafter set forth.

The invention is satisfactorily illustrated in the accompanying drawing, but the important instrumentalities thereof may be varied, and so it is to be understood that the invention is not limited to the specific details shown and described, as long as they are 20 within the spirit or scope of the claims.

Figure 1 represents a side elevation of a clamp attachable to a faucet, and a fluid heater embodying my invention.

Fig. 2 represents a side elevation of the device at a right angle to Fig. 1, and a partial vertical section on line 2—2 Fig. 1.

Fig. 3 represents a horizontal section on line 3—3 Fig. 2.

Fig. 4 represents a horizontal section of a detached portion on line 4—4 Fig. 1. Fig. 35 5 represents a section of a modification of the device.

Similar numerals of reference indicate corresponding parts in the figures. Referring to the drawings,

40 1 designates the nozzle of a faucet, or in lieu thereof that of a spigot or other supply of water or fluid.

2 designates a device for heating water which is directed thereinto from the nozzle 45 1, as will be hereinafter more fully described.

3 designates a yoke which is open so as to receive a proper portion of the nozzle 1, it having been provided with the thumb or set screw 4 whose point is adapted to engage the side of said nozzle, so that when said screw is tightened the yoke is firmly clamped to said nozzle. As seen in Fig. 3 the yoke is

formed with the converging arms 3^a forming an angular clamp to engage the nozzle 55 thus adapting the same for ready use in connection with nozzles of different diameters.

On the side of the yoke are the gudgeons 5 on which is mounted pivotally the forked angular lever 6 which is provided with the 60 handle 7 whereby said lever may be lowered and raised. On the upper limbs 8 of said lever are gudgeons 9 on which are pivotally mounted the upper ends of the crank arms 10, whose lower ends are pivotally connected 65 with ears 10^a on the conduit 11, the latter thus depending from said arms and being composed of a block of suitable material having therein a vertical inlet 12 to receive the lower end of the nozzle 1, and permit 70

water to flow thereinto, said block having

also a horizontal passage 13 which is in communication with said inlet, and also with

the conveyer pipe 14 which is connected

75 with the sides of said block and the casing

of the heater 2, and communicates with the interior of the latter.

The operation is as follows:

The lever 6 having been raised, the conduit 11 is presented to the mouth of the 80 nozzle and the conduit is raised, so that the yoke 3 passes over said nozzle and when it is in adjusted position the screw 4 is tightened, whereby the yoke is clamped to the nozzle and the conduit is held suspended beneath said mouth. Then the lever is raised 85 whereby as said lever and the arms 10 have different centers the limbs 8 of the lever raise the arms carrying the conduit with the latter, whereby the inlet 12 of the conduit receives the mouth of the nozzle, and said conduit is pressed firmly against said mouth and so held firmly thereagainst, the inlet having therein the packing or gasket 90 15 to form a water tight joint with the 95 faucet.

The heater may in this manner be sustained on the faucet and so when the water is turned on at the faucet it will flow into the conduit and the conveyer, and from 100 thence into the heater 2, where it may be heated, in which condition it may be discharged through the pipe 16 where required.

When the lever is lowered, the conduit descends and is removed from the mouth of 105 the faucet. The screw 4 may be loosened

and so the yoke 3 with its attachments may be disconnected from the faucet and with it the heater 2.

In Fig. 5 I show the conduit 11 provided with a threaded sleeve 17 for connection therewith of a hose, for directing fluid into said conduit from the latter to a place of use.

In this case, the sleeve 17 is adapted to have the coupling 18 of the hose 19 secured thereto. The passage 13 in the conduit 11 of the other figures is dispensed with, and the vertical inlet 12 is extended upwardly forming the nipple 20 which is adapted to enter the end of the nozzle 1, said conduit being adapted to be clamped to said end of the nozzle as shown in the other figures, it being seen that the fluid from the faucet, etc., flows therefrom through the conduit 11 into the hose, and by the latter may be directed to the place of service.

Having thus described my invention what I claim as new and desire to secure by Letters Patent, is:—

25 1. A fluid receiver, crank arms pivotally

connected therewith, a lever pivotally connected with said arms, and a clamp detachable to a member of a fluid-supply device and to which said lever is pivoted with its pivot intermediate the pivots of said lever and arms.

2. A fluid receiver, crank arms pivotally connected therewith, a lever pivotally connected with said arms, and a clamp detachable to a member of a fluid-supply device and to which said lever is pivoted with its pivot intermediate the pivots of said lever and arms, said clamp having converging arms to engage said member.

3. A fluid receiver, a yoke open to receive a nozzle and having converging arms, a set screw to force said nozzle between said arms, a lever pivotally mounted on said yoke, and having limbs extended beyond its pivot, and arms pivotally connected to said fluid receiver and to said limbs.

ANTONIO PAPINI.
